UNITED STATES PATENT OFFICE

EDWIN JUELSON, OF CHICAGO, ILLINOIS

VACUUM CLEANER

Application filed November 9, 1928. Serial No. 318,159.

This invention relates to vacuum cleaners and has for its object the provision of a new and improved type of cleaner which shall be simple to construct, easier to empty and 5 quieter in operation than other machines; the provision of a machine of this character having a new and improved form of dust separator, and a new arrangement of air outlet; the provision of a device which can be 10 made and assembled more cheaply than other machines; the provision of a machine in which the filtering device is less susceptible to clogging, and if clogged is more easily cleansed than other machines; the provision 15 of an electric vacuum cleaner having improved arrangements for cooling the motor; the provision of a cleaner having a new and improved blowing arrangement; while further objects and advantages of the invention 20 will become apparent as the description proceeds.

In the drawings accompanying and forming a part of this application I have shown an illustrative embodiment of my invention. 25 Fig. 1 is a vertical sectional view through a complete assembled cleaner embodying my improvements; Fig. 2 is a view similar to Fig. 1 showing the mode of separating the parts for the removal of litter and showing the filter cell in side elevation; Figs. 3 and 4 are 30 horizontal sectional views corresponding to the lines 3—3 and 4—4 of Fig. 1 respectively; and Fig. 5 is a detail view partly in elevation and partly in section of a portion of the device shown in Fig. 1 illustrating the use of the 35 machine as a blower.

The machine of this invention relates to that type of vacuum cleaner sometimes called the "can-type" wherein the fan and dust separator are carried in a portable casing from 40 room to room, but remains substantially stationary during the time that the actual cleaning is being effected, the floor nozzle being connected to the suction inlet by means of a 45 suitable hose. In the present embodiment the can has cylindrical side walls 1 connected to a flat, circular bottom 2 provided with suitable pads or casters 3 and also provided at the center with a perforated area 4 above 50 which is a circular socket 5.

Detachably secured to the mouth of this can is a cover, sealed by a gasket 6, and held in place by any suitable means such for example as clamping bolts 7. This cover is made hollow to define the fan chamber, and 55 itself carries the motor, suction inlet, and other essential parts. In its present embodiment it comprises a substantially flat circular plate 10, a circular ring 11 detachably fastened thereto, and embracing the wall member 12 of the fan chamber, and a flat circular top plate 13 which constitutes the cover of the fan chamber and has a central inlet opening 14. Secured to the bottom face of the plate 10 and depending centrally therefrom 60 is the frame 15 of an electric motor whose armature shaft 16 projects into the fan chamber 17 and is there provided with a suitable fan, preferably comprising blades 18 carried by a circular plate 19 which is inset 65 in a recess 20 formed in the plate 10. Detachably secured to said plate, (as by screws 24) and surrounding the motor frame at some little distance is a cylindrical frame 25 70 of perforated metal (either sheet metal or screen cloth) having secured to its lower end a bottom plate 27 centrally apertured at 28 and provided around that aperture with a yielding extension 30 adapted to fit in the socket 5. The plate 27 is spaced sufficiently 75 from the wall 1 to define therewith a litter chamber 31. The extension 30 is preferably of a yielding nature in order to make a tight fit in the socket 5 without requiring unduly accurate manufacture and location of the 80 cover and in the present embodiment is made of a piece of rubber pipe. The exterior of the member 25 is covered by a piece of porous cloth, paper, or other fabric 32 which is 85 pervious to air but substantially impervious to dust. It can be held in any suitable manner, the simplest mode being by the use of garter springs 33.

The wall of the fan chamber is formed with a discharge opening 35 outside the member 25 and communicating with the chamber 31. The top face of the cover 13 is formed with a cylindrical neck 36 surrounding the inlet opening 14 and serving for the attachment of the collar 37 to which is attached the circu- 90 95 100

lar, cylindrical, transparent, inspection-window 38 generally made of celluloid and riveted thereto. Tightly secured to the upper end of this window is the socket member 40 of a swivel joint whose companion member comprises a head 42 rotatably secured in this socket and a bent neck 43 leading to the hose receiving nipple 44.

Electric current is led to the motor by 10 means of the flexible conductor 45 operatively connected to a switch 46 carried by the cover 13. Also carried by said cover 13 opposite the opening 35 I have shown an upstanding hollow blower neck 47 adapted to receive 15 either a cap 48 for closing it or a blower hose 49. The suction hose for the floor nozzle (not shown) is illustrated at 50.

The operation of the fan draws air and litter in through the hose 50, inspection window 38, and inlet 14, and discharges the same into the chamber 31, whence the air passes out by way of the extension 30 and discharge outlet 4. This air-flow serves to keep the motor cool, and allows the use of a 25 smaller and lighter unit than otherwise. Also the swirling movement of the air as it leaves the fan chamber, causes the greater part of the litter to be separated from the air by centrifugal action with the result that the 30 greater part of the same becomes piled about the outer wall of the can, and the filter fabric is required to perform only a minimum of dust separation. Accordingly the machine shows a minimum of back pressure, and continues to function satisfactorily until the 35 chamber 31 is largely filled with litter.

In order to empty the latter it is merely necessary to remove the top plate as shown in Fig. 2, whereupon the can constitutes a 40 very convenient pail or container which can be carried to a suitable emptying place. To this end I preferably provide a suitable bail 51. Owing to the peculiar mode of centrifugal separation the fabric 32 receives a minimum of clogging but when necessary can be 45 easily brushed owing to its smooth support upon the member 25. Also it can readily be removed, for washing, or replaced, merely by removing the springs 33.

50 In case a blower be desired it is necessary merely to shift the hose from the nipple 44 to the nipple 47. A blast of air sufficient for most purposes can be obtained without the need of closing either of the openings 4 or 55 35 although a stronger blast can be obtained by so doing. There is no apparent tendency for litter previously collected in the chamber 31 to return to the fan chamber while using this blower even when the opening 35 is left 60 unobstructed.

The present machine can be made almost entirely of sheet metal and die castings, with a minimum of sand castings, buffing, and machine work. The motor frame need not be 65 finished nor made expensively.

It will be understood that many changes in detail can be made, that the parts may vary in shape, that the distribution of cast parts and sheet metal can differ from that illustrated, that proportions may be altered, and in general that I do not limit myself in any wise except as specifically recited in my several claims which I desire may be construed broadly, each independently of limitations in other claims.

Having thus described my invention what I claim is:

1. In a vacuum cleaner, a hollow receptacle, a cover removably attached thereto and a filter cell carried by said cover and extending 80 into said receptacle and spaced from the receptacle walls to define a litter-space, a pump carried by said cover, the outlet from said pump discharging eccentrically into said litter-space so as to cause a swirling of the litter around said receptacle, and an outlet from said cell-interior to the open air.

2. In a vacuum cleaner, a hollow receptacle, a cover therefor, a filter cell carried by and depending from said cover, a conduit 90 leading from said cell to a discharge opening in a wall of said receptacle other than said cover, and an inlet for air and litter communicating with the space around said cell.

3. In a vacuum cleaner, a hollow receptacle, a cover therefor having a chamber, a fan in said chamber, a motor carried by said cover and projecting into said receptacle, there being an annular space for litter between said motor and the receptacle wall, 100 said receptacle having an air outlet, and a filter screen interposed between the litter space and outlet, said chamber having an opening into said litter-space at one side of said motor.

4. In a vacuum cleaner, a hollow receptacle, a cover therefor having a chamber, a fan in said chamber, a motor carried by said cover and connected to said fan, and a filter cell carried by said cover and projecting into said receptacle, the space between the walls of said cell and receptacle defining a litter-space and communicating with the outer part of said fan chamber, said fan chamber having an inlet opening opposite 115 the fan and the interior of said filter cell being in communication with the open air.

5. In a vacuum cleaner, a hollow receptacle, a cover therefor having a chamber, a fan in said chamber, a motor carried by 120 said cover and connected to said fan, a hollow foraminous frame carried by said cover and projecting into said receptacle, porous filtering fabric carried by said frame and spaced from the wall of the receptacle to 125 define a litter-space, said fan chamber having an inlet opening and an outlet opening which communicates with said litter-space, and the interior of said frame communicating with the open air.

6. In a vacuum cleaner, a hollow receptacle having side and bottom walls, a bail pivoted inside said side walls, a cover for the open end of said receptacle, said cover having a chamber, a fan in said chamber, a motor carried by said cover and connected to said fan, said motor projecting into said receptacle, and there being an annular litter space around said motor, said fan chamber having an air inlet opposite said fan and an outlet connecting with said litter space, a passageway leading from said litter space to the outer air, and a filter screen traversing said passageway.
- 5 7. In a vacuum cleaner, a hollow receptacle having side and bottom walls and a removable cover, said bottom having an outlet opening and said cover having a chamber, a fan in said chamber, a motor carried by said cover and connected to said fan, a hollow foraminous frame carried by said cover and projecting into said receptacle and communicating with said outlet opening, and filtering fabric carried by said frame and spaced from the side wall of said receptacle to define a litter space, said fan chamber having a discharge opening communicating with said litter space and also having an inlet opening.
- 10 8. In a vacuum cleaner, a hollow receptacle, a cover therefor having a chamber, a fan in said chamber, a hollow foraminous frame carried by said cover and projecting into said receptacle, a motor carried by said cover and projecting into said frame, said frame being spaced from said motor to define an air passageway and from the receptacle wall to define a litter-space, and filtering fabric carried by said frame, there being a passageway from said frame interior to the open air and from said fan chamber to said litter space.
- 15 9. In a vacuum cleaner, a hollow receptacle having side and bottom walls, a removable cover for said receptacle; a fan casing, a motor and a foraminous frame all carried by said cover, said frame surrounding and spaced from said motor and also projecting into said receptacle and defining with its side walls a litter-space, and a fan in said chamber operatively connected to the motor, said fan casing having an inlet opening opposite to said motor and an outlet opening communicating with said litter-space and one of the walls of said receptacle having an air egress opening communicating with the interior of said foraminous frame.
- 20 10. In a vacuum cleaner, a receptacle having a chambered cover, a fan in the chamber, a motor carried by said cover and depending into said receptacle and operatively connected to said fan, a filter fabric inside said receptacle and defining with the side walls thereof a litter-chamber, one wall of
- 25 said receptacle having an outlet opening with which communicates that side of said fabric which is opposite said litter-chamber, and the fan chamber having an inlet opening in that wall which is opposite said motor.
- 30 11. A vacuum cleaner comprising a pail-like receptacle having a removable cover, means securing said cover to said receptacle, a fan casing, a supporting frame and a motor carried by said cover, said frame surrounding said motor and both said frame and motor projecting into said receptacle, a filter fabric attached to said frame, an outlet conduit carried by said frame and communicating with the outer air, and a fan in said fan casing operatively connected to said motor, said fan casing having an outlet opening into a part of said receptacle and an inlet opening on the side which is opposite said motor.
- 35 In testimony whereof I hereunto affix my signature.
